UNITED STATES PATENT OFFICE.

EMMA F. BARRI, OF BROOKLYN, NEW YORK.

STOCKING-SUPPORTING CLASP.

1,324,720.

Specification of Letters Patent.

Patented Dec. 9, 1919.

Application filed May 10, 1919. Serial No. 296,072.

To all whom it may concern:

Be it known that I, EMMA F. BARRI, a citizen of the United States, residing at Brooklyn, in the county of Kings and State of New York, have invented new and useful Improvements in Stocking-Supporting Clasps, of which the following is a specification.

This invention relates to hose supporters and more particularly to a means for clasping and retaining the stocking to the supporter.

One of the principal objects in view is the provision of a clamp or clasp comprising a pair of mating members having relatively wide engaging portions whereby to distribute the strain over a large surface of the stocking in order to prevent tearing of the same.

Another object of the invention is the provision of a device of the class described which will be more comfortable to the wearer and which will eliminate the use of a plurality of supporters for each stocking.

A further object of the invention is the provision of means on one of the elements which co-acts with the other element to prevent casual displacement of the clamp from the stocking when the pull on the same is released as is the case when the wearer assumes a sitting position.

A still further object of the invention is the provision of a device of the class described which is of simple construction, inexpensive to manufacture and which is thoroughly reliable and efficient in purpose.

With these and other objects in view, the invention resides in the novel construction, combination and arrangement of parts which will be readily apparent from the following description and claims when taken in connection with the accompanying drawings in which:

Figure 1 is a perspective view showing the device in its applied position.

Fig. 2 is a similar view showing the device removed from the stocking.

Fig. 3 is a sectional view on the line 3—3 of Fig. 2.

Referring to the drawings by characters of reference, 10 designates the usual elastic supporter to which the clasp is attached by means of the link-loop 11. The clasp comprises a flexible tape 12 which is passed through the slots 13 and 14 of a base member 15, the latter being preferably con-

structed of metal, celluloid or any other suitable material which will answer the purpose. A clamping portion 16 is formed on the base member 15 or secured thereto in any preferred manner to provide an upstanding wall 17 having an overhanging rounded flange 18 and laterally extending projections or wings 19, the purpose of which will be hereinafter described. A clamping bail 20 is secured to the flexible tape 12 adjacent to its uppermost end and is provided with a clamping portion 21 which is preferably corrugated as clearly shown in Fig. 2 of the drawing. The portion 21 is adapted to clamp the upper end of the stocking against the wall 17 and the side branches 22 of the bail are adapted to co-act with the wings 19 in order to prevent casual displacement or release of the bail when the same is arranged in its clamping position on the stocking. Normally, the strain exerted on the bail tends to force the same against the wall 17 when the wearer is in an upright position but when in a sitting position, the elastic becomes slack and for this purpose the side projections or wings 19 function to frictionally retain the bail against displacement; said projections or wings being resilient. If desired, a slide 23 may be employed for the purpose of crowding the side branches 22 of the bail against the projections or wings by sliding the same toward the portion 21 as will be readily understood.

By providing a relatively wide gripping portion as illustrated, the strain will necessarily be distributed over a greater surface of the stocking, thus eliminating what are known as "runs", and in applying the device, it has been found very satisfactory to first engage one side branch 22 of the bail over its corresponding projection or wing 19 and then snapping the same over the remaining projection or wing.

While I have illustrated and described a simple and preferred form of carrying my invention into practice, I do not care to be limited to the precise details therein exhibited, but desire to have it understood that such changes and alterations as fall within the scope of the appended claims may be resorted to when desired.

What is claimed as new is:—

1. A clasp comprising a flexible suspending element, a base carried thereby, a long clamping portion fixed with respect to and

- extending lengthwise from a point adjacent to one side edge of the base to a portion adjacent to the opposite side edge thereof and having a lip spaced from the face of the base
5 and also having resilient projections that extend laterally beyond the ends of the lip and the side edges of the clamping portion, and a broad and open bail connected with the flexible element and having an outer
10 transverse clamping end portion, and also having side clamping portions adapted to be opposed to and yieldingly held by friction to the resilient projections at the ends of the clamping portion.
15 2. A clasp comprising a base, a clamping portion fixed to and extending from the face of the base and having a lip spaced from the face of the base and also having projections extending beyond the ends of said lip, a
20 flexible element to suspend the base, and a broad, open bail connected to the flexible element and having a transverse portion to coöperate with said lip and also having side portions to clamp a stocking against the said
25 projections.
3. A clasp comprising a base, a clamping portion fixed to and extending from the face of the base and having a lip spaced from the face of the base and also having projections
30 extending outwardly beyond the ends of

said lip, and a broad, open, swinging bail associated and connected with the base and having a transverse portion to coöperate with the lip and also having side portions to coöperate with the said projections; said bail in its working position receiving the clamping portion to enable its side portions to coöperate with said projections and its end portion to coöperate with the clamping portion within said link. 35

4. A clasp comprising a base having an aperture adjacent to its outer end, a clamping portion fixed to and extending from the face of the base and having at its outer end a transverse lip spaced from the face of the base and also having resilient projections extending beyond the ends of said transverse lip, a flexible element to suspend the base; said element having a loop passed through said aperture of the base and also 45 having a portion arranged opposite said lip, and a broad, open, bail connected with the flexible element at a point remote from the base and having a transverse portion to coöperate with said lip and also having side 50 portions to clamp a stocking against the said projections. 55

In testimony whereof I have affixed my signature.

EMMA F. BARRI.
